UNITED STATES PATENT OFFICE.

WILLIAM A. BUCHANAN, OF ASHEVILLE, NORTH CAROLINA.

COMBINED HEEL-PLATE AND SHANK-BRACE.

1,277,289.

Specification of Letters Patent. Patented Aug. 27, 1918.

Application filed September 12, 1917. Serial No. 191,014.

To all whom it may concern:

Be it known that I, WILLIAM A. BUCHANAN, a citizen of the United States, residing at Asheville, in the county of Buncombe and State of North Carolina, have invented certain new and useful Improvements in Combined Heel-Plates and Shank-Braces, of which the following is a specification.

My invention relates to new and useful 10 improvements in attachments for shoes, the primary object of my invention being the provision of an improved combination heel plate and shank brace for use particularly in ladies' shoes having high French heels.

15 Heretofore considerable trouble has been caused due to the heels pulling away from the heel seats when in use, serious accidents sometimes occurring as the result, and one of the primary objects of my present invention consists in constructing a device which may be applied to the shoe during its manufacture or to shoes already made and which will hold the heels and shanks of the 20 shoes in proper shape and which will secure 25 the heel so that it cannot come off.

In this connection a still further object which I have in view is the provision of a metallic heel plate and shank brace which may be inserted between the inner and outer 30 soles of the shoe and through which screws may be passed into the top of the heel to securely lock the heel in place.

With these and other objects in view, my invention will be more fully described, illustrated in the accompanying drawings and then specifically pointed out in the claim which forms a part of this application.

In the drawings:—

Figure 1 is an elevation, partially in section of a shoe showing my invention applied;

Fig. 2 is a perspective view of the heel plate and shank brace.

Fig. 3 is a transverse sectional view taken 45 on the line 3—3 of Fig. 2;

Corresponding and like parts are referred to in the following description and indicated in all the views of the drawings by the same reference characters.

50 As best shown in Fig. 2 of the drawings my improved heel plate and shank brace comprises a body 10 of relatively thin sheet metal of suitable strength and resiliency conforming in shape and size to the shape

and size of the heel seat of the shoe with 55 which it is to be employed. This body is slightly concavo-convex to conform to the shape of the heel seat and at its front is provided with a projecting tongue 11 which forms a shank brace and which curves downwardly to correspond to the curvature of the shank of the shoe. This tongue is arched transversely throughout practically its entire length and at its free end is widened laterally to provide an attaching head 12. 60 This attaching head 12 is formed with openings 13 through which suitable fastening devices, such as tacks or the like may be passed and the heel plate 10 is formed with similar openings 14 to receive screws, as will be later 65 explained. As best shown in Fig. 2 the free end of the tongue is cut at a slight angle and the lateral extension of the tongue is more pronounced at one side than at the other. This is due to the fact that the combined 70 heel plate and shank braces are made in rights and lefts and the attaching head 12 is shaped to properly fit in the central portion of the sole of the shoe immediately at 75 the rear of the ball of the foot. 80

In order to insure a proper understanding of my invention and its use I have illustrated it in Fig. 1 in connection with a conventional shoe 15 having the outer sole 16, inner sole 17, sole lining 18 and heel 19. As 85 there shown the combined heel plate and shank brace is disposed between the inner and outer soles of the shoe and screws 20 are passed through the openings 14 and into the heel 19 to firmly secure the heel in place. 90 Obviously with this arrangement there will be no tilting of the heel 19 relative to the shank portion of the shoe and it will be practically impossible for the heel to pull loose. The combined plate and brace not 95 only braces the shoe and helps keep the shape of the shoe but also serves as a brace for the foot of the wearer. By arching the tongue 11 transversely added strength, for the metal employed, is obtained and the 100 leather of the outer sole will be molded into this arched portion during the manufacture so that the tongue will be held firmly in place.

From the foregoing description it will be 105 apparent that I have provided an extremely simple and efficient form of heel retaining plate and shank brace and one which may

be economically manufactured and readily applied, either during manufacture of the shoe or afterward as desired.

Having thus described the invention, what is claimed as new is:

The combination with a shoe including inner and outer soles and a heel, of a combined heel plate and shank brace interposed between the inner and outer soles of the shoe and comprising a body portion of resilient metal conforming in shape to the shape of the heel seat and slightly concavo-convex, a relatively narrow integral tongue project-

ing from the forward edge of the heel plate and forming a shank brace, the tongue being longitudinally curved to conform to the curvature of the shank of the shoe, and fastening devices passed through the heel plate, outer sole and into the heel, the tongue being transversely arched throughout the greater portion of its length with its concaved face directed downwardly and the outer sole being molded to fill in the cavity thus formed.

In testimony whereof I affix my signature. 25
WILLIAM A. BUCHANAN.
